CLAIM

The ornamental design for a robot for automatic paint spraying or the like, substantially as shown and described.

DESCRIPTION

FIG. 1 is an isometric view of a robot for automatic paint spraying or the like showing my new design, the bottom being unornamented and the tubing being shown broken away to indicate indeterminate length; FIG. 2 is a side elevational view taken from the left of FIG. 1;

FIG. 3 is a side elevational view taken from the right of FIG. 1;

FIG. 4 is a front elevational view thereof;

FIG. 5 is a top plan view thereof; and

FIG. 6 is a rear elevational view thereof.

FIG. 1

FIG. 2

FIG. 3

FIG. 4

FIG. 5
